EMIL DEISTER AND WILLIAM F. DEISTER, OF FORT WAYNE, INDIANA, ASSIGNEES
TO DEISTER MACHINE COMPANY, OF FORT WAYNE, INDIANA, A CORPORATION.

SUPPORTING MECHANISM FOR ORE-CONCENTRATORS.

1,382,276.

Specification of Letters Patent. Patented June 21, 1921.

Application filed November 17, 1919. Serial No. 338,722.

To all whom it may concern:

- Be it known that we, EMIL DEISTER and WILLIAM F. DEISTER, citizens of the United States, residing at Fort Wayne, in the county of Allen and State of Indiana, have invented new and useful Improvements in Supporting Mechanism for Ore-Concentrators, of which the following is a specification.
- 10 The invention relates to ore concentrating machinery and particularly to mechanism for supporting reciprocating concentrating tables, and its object is to provide a mechanism by which such table shall be effectively supported for reciprocation and by which the table may be adjusted in its inclination with ease and accuracy, the mechanism having great durability and a wide range of adjustment.
- 20 In the accompanying drawings we have illustrated the preferred form of the invention in which—

Figure 1 is a side elevational view of the supporting mechanism with a table thereon; Fig. 2 a plan view of the mechanism; Fig. 3 a plan view of one of the adjustable supports of the mechanism; Fig. 4 a cross-section on line 4—4 of Fig. 3; Fig. 5 a cross-section on line 5—5 of Fig. 3; Fig. 6 a cross-section on line 6—6 of Fig. 4 and Fig. 7 a cross-section on line 7—7 of Fig. 2.

Referring to the drawings the supporting mechanism consists of a suitable number of adjustable supports 10 and a suitable number of fixed supports 11, the number of such supports to be used being determined by the size of the table to be supported. 12 indicate channel beams suitably secured to foundation piers 13, extension 14 of the rear pier being adapted to receive the driving mechanism of the table. Piers 13 extend transversely relatively to the deck so that, as illustrated, supports 10 will be under the feed side of the table 15 and supports 11 under the tailings discharge side, supports 10 being secured to beams 12 at one end thereof and supports 11 to the opposite end. If desired the adjustable supports may be arranged on the tailings discharge side of the deck and the fixed supports on the opposite or feed side, or any other arrangement of the same may be made as desired.

The adjustable supports are alike in construction and in like manner the fixed supports are alike in construction. Each sup-

port 10 consists of a base 16 having laterally extending apertured flanges 17 for the reception of bolts by which the base is fixed to channel 12. Side walls 18 extend upwardly from base 16 a suitable height, the upper edge of the walls being flared to form suitable bearing surfaces for the bearing carrying section of the support, and also to add strength to the said walls. Ribs 19 also strengthen the walls. The space between walls 18 forms a channel extending longitudinally relatively to the table 15 and in this channel and slidably on base 16 is a plate 20 supporting a plurality of wedges 21 and 22. Preferably the wedges are integral with plate 20 and the wedges 21 are arranged at opposite corners of one end of the plate and wedge 22 in the middle of the opposite end of the plate. The wedges are parallel and they all slope in the same direction. Any suitable number of the wedges may be used but we prefer the arrangement illustrated as well adapted for general use since the three points of support for the bearing carrying support or section of the support furnished by said wedges readily balances the section and requires little attention to secure alinement of the same. The wedges are, of course, the same in height and slope.

85 The bearing carrying section 23 consists of a box-like structure 24 having in its bottom and projecting upwardly therefrom a laterally concaved bearing 25. The wall 26 about the bearing forms a reservoir for lubricant for continuously lubricating the same and the upper bearing portion 27 depending from and rigidly secured to the bottom of deck 15. The lower face of bearing portion 27 is convex and reciprocates with 95 the table on bearing 25. The concavity of bearing 25 and the convexity of bearing portion 27 assure continuous contact of the two bearings irrespective of the inclination of table 15. Legs 28 depend from box 24 at one 100 end thereof and rest at their lower ends on wedges 21 respectively, the legs being of sufficient width to overlap the adjacent ends of walls 18 on base 16 in order to limit the movement of the box down the slope of said 105 wedges, the tendency of the box being to slide down said slope when the wedges engage the said legs. Wall 29 depends from the box at the opposite end thereof, its lower edge contacting with the sloping side of 110

wedge 22, and said wall together with legs 28 coöperate with walls 18 so that the box with its bearing are guided by the walls in their vertical movement caused by the movement of the wedges when plate 20 is moved in the channel between walls 18 of base 16.

In order that the several wedge carrying plates 20 shall be moved simultaneously for simultaneously raising or lowering the bearing-carrying sections of supports 10 we provide rod 30 having at one end a hand wheel 31 by which it may be rotated. The rod is loosely passed through aperture 32 in wedge 22 of each plate and through an apertured lug or rib 33 also on each plate, and it is also threaded through a lug 34 projecting upwardly from base 16 through a suitable slot or opening in plate 20 of one of the adjustable supports. In the drawings 20 the hand wheel is secured to rod 30 on the end thereof adjacent the mineral discharge end of the table and lug 34 is formed on the support 10 adjacent the head or motion end of the table. In this arrangement of supports 10 the rod is connected to the wedge carrying plate of the latter support by lock nuts 35 on the end of the rod and by collar 36 on the rod at the opposite end of the plate. The intermediate wedge carrying plate 30 is secured to the rod by collars 37 secured to the rod at opposite ends of the plate and the forward wedge carrying plate is connected to the rod by collar 38 and the hand wheel. It is apparent that by rotating the hand 35 wheel and rod the threaded lug 34 compels the rod to move longitudinally and carry with it the several wedge carrying plates. If the movement of the rod is forward or toward the mineral discharge end of the 40 table the wedges will cause the bearing-carrying section of each support 10 to rise and elevate the feed side of the table, the table pivoting on the fixed bearing supports along the opposite side of the table. In this manner any desired transverse inclination 45 of the table may be accomplished. Any suitable form of cams for elevating or lowering the bearing carrying sections of supports 10 will suffice, the wedges illustrated 50 being only one form adapted for the purpose.

Each support 11 consists of a box or pot like structure 39 having at its base laterally projecting apertured flanges 40 to receive bolts by which the structure is rigidly secured to channel 12. At a suitable distance below the open top of the box is a partition 41 carrying a transversely concaved bearing 42 similar to bearing 25 of support 60 10, the upper portion of the side walls of the box forming a reservoir for lubricant

for continuously lubricating the bearing. An upper bearing similar to bearing 27 is rigidly secured to the table and reciprocates on bearing 42 in the same manner as bearing 27 reciprocates on bearing 25. Each support 11 being rigidly secured to a channel 12 and bearing 42 being secured to or integral with the support no adjustment of the bearing is possible and none is desired since it is 65 desired that the table shall pivot on the fixed supports as the opposite side of the same is raised or lowered by the adjustable bearing supports. Supports 11 also maintain the longitudinal alinement of the table irrespec- 70 75 tive of the degree of inclination of the same.

In order that the reservoirs for lubricant for bearings 25 and 42 shall be protected from foreign matter we provide integrally with upper portion 27 of each bearing a laterally extending flange 27^a (Fig. 4) having a depending flange or rim 27^b, the flange and rim overhanging the upper edge of the reservoir wall and serving to exclude all objectionable foreign matter from the reservoir. 80 85

The arrangement of the supports will be that best suited or most convenient for the table to be supported and the position it may occupy in the mill. For example, it 90 may be more convenient to have the hand wheel at the head or motion end of the table to accomplish which change it will be necessary only to reverse the order of the adjustable supports, the wedge carrying plates, 95 of course, being set in proper position to elevate the movable bearing-sections of supports 10 when the rod is rotated for regulating the inclination of the table.

What we claim is:

In supporting mechanism for ore concentrating tables, the combination of a plurality of bearings rigidly fixed beneath one side of the table upon which the table pivots and reciprocates, a plurality of adjustably supported bearings beneath the opposite side of the table each comprising a hollow base section, a bearing carrying section vertically movable in the base section, a reciprocable member supported in the base section and carrying three wedges adapted to engage the lower end of the bearing-carrying section at three points and means connecting all the wedge carrying members for simultaneously operating the same to control the 100 105 110 115 inclination of the table.

In witness whereof we have hereunto subscribed our names this 15th day of November, 1919.

EMIL DEISTER.
WILLIAM F. DEISTER.
